UNITED STATES PATENT OFFICE.

JEAN B. BERGOUGNOUX, OF CHICAGO, ILLINOIS.

AUXILIARY FEEDING DEVICE FOR INTERNAL-COMBUSTION ENGINES.

1,299,817.

Specification of Letters Patent.

Patented Apr. 8, 1919.

Application filed September 15, 1917. Serial No. 191,524.

To all whom it may concern:

Be it known that I, JEAN B. BERGOUGNOUX, a citizen of the United States, and a resident of the city of Chicago, county 5 of Cook, and State of Illinois, have invented certain new and useful Improvements in Auxiliary Feeding Devices for Internal-Combustion Engines, of which the following is a specification.

10 My invention relates to the feeding of engines of the internal combustion type and more particularly to an auxiliary device that is connected to and discharges a suitable vapor into the intake manifold of a gasolene 15 engine. The objects I have in view are to provide a feeding device of this character that is both simple in construction and easy to manipulate and is also one that comprises few parts so that it may be economically 20 manufactured and can be sold for a moderate price. It is also an object of my invention to provide suitable means whereby the quantity of vapor discharged from the device may be regulated or adjusted to a nicety 25 and may be turned on or cut off whenever desired. Owing to the construction and arrangement of the parts of my device, I am enabled to attain divers results from its operation. For example, the vapor 30 charged into the manifold by my device may be charged with water or gasolene for the purpose of modifying the gaseous mixture from the carburetor, or for the purpose of cleaning the pistons and cylinders, etc., the 35 vapor may be charged with kerosene or a carbon removing compound,—in fact, any suitable liquid may be placed in the reservoir of my device and the vaporized mixture fed to the manifold.

40 I prefer to accomplish the objects of my invention by substantially the mechanism hereinafter described, whereof a diagrammatic illustration is disclosed in the accompanying drawings that form a part of this 45 specification, wherein,—

Figure 1 is an elevation of my device attached to the manifold of an internal explosive engine, the latter being shown in a fragmental manner.

50 Fig. 2 is a central vertical section of my device drawn to a larger scale.

In the drawings I have shown a fragment of a typical engine, A, having an inlet manifold, B, leading thereto from a well-known 55 form of carburetor C.

Referring to the drawings, it will be seen

my invention preferably comprises a cylindrical chamber or reservoir 5 that consists of a tube or hollow cylinder of glass or other suitable material, the ends whereof are 60 closed by caps 6 and 7, having flanged edges that extend over the sides of the tube. The lower cap 6 has a screw-thread connection with a post 8, that arises vertically from the center thereof and extends axially through 65 chamber 5 where it is screwed into an internally and externally threaded boss 9 projecting from the upper surface of the opposite cap 7, and suitable washers or gaskets 10, of rubber, leather, "fiberoid" or the 70 like, are interposed between the ends of the tube and the interior surfaces of the caps in order to prevent leakage and to avoid breaking the glass. A pair of clamping nuts 11 are screwed onto the exterior threads of boss 75 9 in order to clamp the device to a suitable bracket or other support 12, whereby the feeding device may be conveniently mounted adjacent the manifold of the engine. The upper end of post 8 is bored to provide an 80 L-shaped passage x—G, the shorter or lateral portion x whereof opens into the chamber 5, adjacent the top thereof or above the liquid level, while the longer vertical portion G of said passage communicates with 85 the boss 9 or the top of cap 7.

Adjacent the boss 9 is an air inlet device that consists of a pipe 13 that is enlarged and threaded adjacent its upper end and tapped into a threaded boss 14 also arising 90 from the upper surface of the top cap 7. The lower end of pipe 13 is cut obliquely, as shown, and terminates adjacent or above the bottom of chamber 5 in order that its end will be immersed in the fluid or liquid that 95 is contained in said chamber, while the opposite or upper end of said pipe is provided with an inlet cock 15, the adjustment of which latter regulates the quantity of air admitted to the chamber 5.

100 A suitable elbow 16 is tapped into the outer end of the bore of boss 9 and has its lateral member connected by means of a sleeve nut 17 to a suitable discharge pipe 18, with which it communicates. One member 105 or branch of an elbow 19 is connected by a sleeve nut 20 to the opposite end of discharge pipe 18, while the other branch or member of said elbow is tapped into a suitable threaded inlet opening made in a convenient portion of the manifold B of the engine A. In order to permit the discharge 110

of the vapor from the chamber into the manifold and to prevent back pressure reaching the chamber 5, I have provided a suitable check valve 22, which I have shown 5 as being disposed upon the elbow 16, but it will be understood it may be mounted at any convenient place in the discharge passage between the chamber 5 and the manifold.

In operation, the chamber 5 is filled with 10 a suitable liquid by removing the air inlet device, and after the cylinder has been filled to a suitable height, said inlet device is screwed into position again and the cock 15 is adjusted to permit air to enter there- 15 through and into the chamber. The suction from the manifold will cause the air to bubble or surge through the liquid from the lower end of pipe 13 and rise or pass out of the liquid charged with a vapor, where it 20 will be drawn off through the L-shaped passage x—G that is located above the level of the liquid. The vapor will then be drawn through pipe 18 past the check valve and into the manifold. When kerosene is used 25 in the chamber 5, the vapor produced by the bubbling of the air through the same will be utilized in cleaning the valves and pistons of the engine, and likewise when the chamber is filled with carbon remover, the vapor 30 therefrom will assist in keeping the cylinders of the engine free of carbon accumulations. In fact, the device may be employed for modifying the feed in any manner through the graduated control of the intro- 35 duction of air or vapor.

It will be understood that I do not limit myself to the precise structure disclosed herein, for it is obvious that divers modifications may be made without materially de- 40 parting from the spirit of my invention. All such changes are contemplated within the scope of my invention as expressed in the appended claims.

What I claim is:—

1. An auxiliary feeding device for internal 45 combustion engines comprising a cylinder, closures for the ends of said cylinder, means extending between said closures adapted to clamp them upon the ends of said cylinder, said upper closure having an outlet passage- 50 way therethrough and an inlet port, a pipe mounted in said inlet port and extending from adjacent the bottom of said reservoir to the outside of said upper cap, a regulating cock on said pipe outside said reservoir, and 55 means for establishing communication between the outlet port in said upper cap and the inlet manifolds of the engine.

2. An auxiliary feeding device for inter- 60 nal combustion engines comprising a cylinder, caps closing the ends of said cylinder, a central post having threaded connections with said caps, said post having an L-shaped passage leading from adjacent the lower face of the upper cap to the exterior of said cylinder, a port in said upper cap, a pipe mounted in said port and extending from adjacent the bottom to the outside of said cylinder, a regulating cock on said pipe outside of said cylinder, a hollow stub on 70 the upper surface of said upper cap and communicating with said L-shaped passage, bracket clamping nuts threaded on said stub, a discharge pipe screwed into said stub and establishing communication between said L-shaped passage and the manifold of the engine, and a check valve in said discharge pipe adjacent its connection with the manifold.

Signed at Chicago, county of Cook, and State of Illinois, this 25th day of August, 1917.

JEAN B. BERGOUGNOUX.
